MULTIPLE PENCIL, ESPECIALLY FOR
MAKE-UP STICKS

Karl Heinrich Heinz, Pforzheim, Germany

Application October 10, 1936, Serial No. 105,132
In Germany October 12, 1935

10 Claims. (Cl. 132—79)

Multi-color pencils are known having exchangeable lead carriers which, by means of knobs 5 slidable in guide slots in the pencil case and engageable in notches, can be separately pushed out of their inoperative position into the position for use and returned from this position for use into their inoperative position, and in each of which the individual leads are shiftable by means of a screw mechanism. The use of these pencils, 10 for which leads, especially colored leads of relatively great thickness, are required, presented difficulties which increased when it was endeavoured to employ such a multi-color pencil for make-up sticks. The make-up sticks consist of 15 a very soft substance and therefore break very easily. Consequently, care must be taken to return the stick into its carrier after use. Moreover, owing to the softness of the sticks, they very easily soil the fingers. For this reason it is 20 not practical to move the sticks, in the manner customary in the case of multi-color pencils, by gripping the front end of the lead carrier, which generally only projects slightly from the pencil case, with the fingers, which consequently come 25 into contact with the lead also.

All the requirements above enumerated are met by the invention which relates to a multiple pencil, especially for make-up sticks, with exchangeable stick carriers which, by means of slides guided 30 in slots in the pencil case and engageable in a notch, can be pushed forward out of their position of rest into their position for use and returned into their position of rest, and in each of which carriers a stick is shiftable by means of 35 a screw mechanism. The invention is characterized in that the rotatable part of each stick carrier has at its front end at least one lateral projection or the like, that the conical point of the pencil case is rotatable and has in its interior 40 at least one catch for engaging the projection when the carrier is pushed forward into its position for use, so that, after this carrier has been pushed forward, the stick can be pushed forwards and backwards in its carrier by the conical 45 pencil case point being turned. The front end of the rotatable part of each stick carrier may be constructed as a multiple thread screw with steep pitch and the conical point of the pencil case may have in its interior longitudinal ribs corresponding to the screw threads. By this arrangement, when a stick carrier is pushed forward, its front end automatically engages the point of the pencil case without it being necessary to turn this point through a large angle of rotation. Owing 50 to the interengagement of the ribs and

threads the point of the stick carrier sits very tightly in the point of the pencil case.

By means of the construction above described it is possible, after a stick carrier has been pushed forward, to bring the make-up stick or the like into its position for use, without it being necessary to grip the point of the stick carrier itself. Only the point of the pencil case has to be turned. The fingers cannot possibly become soiled. Moreover, the stick carrier itself need not project from the point of the pencil case so that the overall length of the pencil is not greater when ready for use than when all the stick carriers are in their position of rest.

A pencil of this type may be constructed in such a manner that the individual stick carriers must be pushed by hand not only into position for use but also pulled back into their position of rest. It is, however, likewise possible to provide one or several return springs (pressure or tension springs) for the stick carriers, so that the carriers slide back out of the position for use into their position of rest under the action of the return springs after disengagement of their locking means. If such return springs are provided and the notches securing the stick carriers in their position of use are formed in known manner as lateral widenings at the front end of the guide slot for accommodating the slide knobs of the stick carriers, it is advisable to arrange the notch widening on that side of the slot that, when the stick has been turned completely back by means of the rotatable pencil case point and after the abutment of the slide sleeve containing the stick, the whole stick carrier is rotated and its slide knob pressed out of the notch. In this manner, by turning the pencil case point, the stick, after being used, is not only turned into its carrier so that it is best protected against fracture, but by the same rotary movement the carrier itself is likewise disengaged from its notch so that it can slide into its position of rest under the action of the return spring.

When employing such a multiple pencil for make-up sticks, it is important that its appearance is as good as possible. It is therefore advisable for the slide knob of each stick carrier to be so long that, when in its position of rest, it covers the whole guide slot and for a blade spring fixed on the stick carrier and carrying the slide knob to cover the inner side of the slot when the stick carrier is in its position for use. The necessary guide slots in the pencil case will then scarcely be visible, and moreover by covering these slots on their inner side by means of the

blade springs even when the pencil is ready for use the penetration of dust and dirt will be prevented.

The constructions of the stick carriers and the return springs and their arrangement may be similar to those known in multiple color pencils. It is still more important for the whole pencil to be as short as possible in the case of make-up stick pencils than in the case of lead pencils.

For this purpose, in the case of multiple stick pencils having a return spring for each stick carrier each return spring may advantageously be accommodated in a tubular sleeve fixed at the side of the stick carrier. The stick carrier and the tubular sleeve may be fixed on the blade spring carrying the slide knob.

In the case of pencils with a separate return spring for each stick carrier, the stationary portions of the stick carriers carrying the return springs may be hooked in slots in a supporting plate. To prevent the stick carriers from wabbling in their slots and thereby to avoid lateral movement of the slide knobs, the thickened ends of the stick carriers bearing against the supporting plate may be accommodated in holes in a holding plate resting on the supporting plate.

Two embodiments of the invention are illustrated by way of example in the accompanying drawing in which:—

Fig. 1 is a longitudinal section through the first form of construction with a stick carrier in position for use and another stick carrier in position of rest.

Fig. 2 is a top plan view of Fig. 1 with the end cap unscrewed and the rear holding plate removed.

Fig. 3 is an elevation of Fig. 1 partly in section and partly broken away.

Fig. 4 is a section on line IV—IV of Fig. 3 without stick carriers.

Fig. 5 shows the rear holding plate in plan view.

Fig. 6 shows a second form of construction of the stick carrier, partly in section.

Fig. 7 is a top plan view of Fig. 6.

Fig. 8 is a bottom plan view of the main parts of Fig. 6.

Fig. 9 is a side view of Fig. 6.

Fig. 10 shows the accommodation of three stick carriers according to Fig. 6 in an outer case.

The multiple pencil comprises in known manner a cylindrical outer case 1 having a cylindrically widened portion 2 at its front end and an external screw thread 3 at its rear end; a short sleeve 4 is slipped over the widened portion 2 and tapers at its front end to a conical point 5. The sleeve 4 is, according to the invention, rotatably connected with the outer case 1 by an inwardly bent flange 6 at its rear end. In the point 5, which is hereinafter referred to as case point, a cone 7 is soldered and has in its front edge longitudinal grooves 8 widening at the rear ends and merging gradually into the body of the cone. Several, in the present instance three, stick carriers are accommodated in the case 1, two of these carriers being designated by 9 and 10 in Fig. 1. A slide knob 12 is attached to each stick carrier by means of a blade spring 11, and the web 13 of each knob is guided in a longitudinal slot 14 in the case 1. The case 1 has three slots 14 corresponding to the number of stick carriers, these slots having at their front ends a lateral widening 15 which forms a stop 16 for the web 13 of the stick carriers 9, 10. The edge of the slot

opposite the widened portion extends obliquely at its front end 17.

Each stick carrier 9, 10 has an outer sleeve 18, 19, the front part 18 of which is wider than the rear part 19. The rear end 20 of part 19 is narrowed and carries the above mentioned blade spring 11. In the part 19 a pressure spring 23 is mounted on a rod 21 with thickened end 22. This rod 21 also has a thickened portion 24 at its rear end. A sleeve 25 is rigidly connected with the front part 18 of the stick carrier 9 and has a helical slot 25'. An inner sleeve 27 with a longitudinal slot 28 is rotatable in this sleeve 25 and held by a shoulder 26 at its rear end. A ring 28 is soldered on the front end of the slotted sleeve 27 and has on its outer side longitudinal ribs 30 which correspond with the longitudinal grooves 8 in the case point 5.

Finally, a small sliding sleeve 31 is mounted in the slotted sleeve 27 and has a transverse pin 32 which engages in the helical slot 25' in the sleeve 25 through the longitudinal slot 28. The front end of sleeve 31 is split and serves for accommodating a make-up stick 33. The sleeve 31 with the make-up stick 33 is moved forwards and back by turning the slotted sleeve 27 by means of the ring 29.

A sleeve 34 is slipped into the rear end of the pencil case 1 which is supported on the rear edge of the case 1 by an outwardly rolled collar 35. A plate 37 provided with three parallel slots 38 (Fig. 2) rests on an inwardly directed bead 36 in sleeve 34. The ends of the rods 21 of the stick carriers are passed one through each of these slots before the plate 38 is inserted in the sleeve 34. A holding plate 39 with three holes 40, accommodating the thickened rear ends 24 of the rods 21, prevents the rod ends from shifting and the slide knobs 12 from wabbling. The holding plate 39 is shown separately in Fig. 5.

A cap 41 is screwed on to the screw thread 3 of the pencil case 1 and holds the sleeve 34 in the case 1 and the plates 37 and 39 in the sleeve 34.

The second stick carrier 10 is shown in position of rest in Fig. 1. Herein the web 13 of the slide knob is in its upper position 13' shown in Fig. 3, the guide slot 14 being completely covered by the sliding knob 12.

When it is desired to use the pencil, the stick carrier 9, for example, is shifted by means of its slide knob 12 into the position in which it is shown in Fig. 1. During this movement the web 13 slides along the oblique edge 17 of the guide slot 14 into the notch widening 15 and bears against the shoulder 16 in the position 13'', at the same time compressing the spring 23. To ensure its sliding smoothly along the edge 17 and on to the shoulder 16, the web 13 is of trapezium-shaped cross-section as shown in Fig. 3, and the shoulder 16 has an oblique edge. During this shifting moving the longitudinal ribs 30 come into engagement with the longitudinal grooves 8 in the case point. If the case point 5 is now turned, the ring 29 and therewith the slotted sleeve 27 will be turned, and the sleeve 31 with the lip stick 33 can be pushed forward so far that it projects from the case point and can be used, as shown in Fig. 1.

When the stick is no longer required, the case point 5 is turned in the opposite direction relatively to the case 1 until the guide sleeve 31 carrying the lip stick reaches its rearmost position and abuts against its guide. If the case point 5 is turned further in the same direction, the whole stick carrier 9 is rotated and the knob web 75

13 forced off the shoulder 16, whereupon the stick carrier 9 springs back into its retracted position of rest under the action of the spring 23. It is then possible to push forward another stick carrier.

5 Figs. 6 to 9 show a stick carrier of modified construction. Therein a slotted sleeve 42 with longitudinal slot 43 is rigidly connected with a blade spring 44. A small sleeve 45 for carrying 10 a lip stick 46 is accommodated in the sleeve 42. A transverse pin 47 fixed in the sleeve 45 extends through the longitudinal slot 43 into a helical slot 48' in a sleeve 48 rotatable on the sleeve 42 and carrying at its front end a ring with slightly 15 oblique helical longitudinal ribs 49'. The blade spring 44 extends radially to the axis of the stick carrier (Figs. 6 and 7) and has an extension 58 (Fig. 7) carrying a tube 51 (Fig. 6) arranged laterally of the stick carrier and extending parallel thereto. A pressure spring 54 is mounted on 20 a rod 53 accommodated in the tube 51 and having a thickened end 52. The rear end of this spring 54 bears against the tapered rear end of the tube 51. The rod 53 projects from the rear 25 end of the tube 51 and has a thick rear end 55 by which the rod is suspended in the case 1. A slide knob 57 is rigidly connected with the blade spring 44 by means of a web 56.

Fig. 10 shows the arrangement of three such 30 stick carriers in the pencil case 1. The advantage of this construction is, that the space necessary for accommodating the springs 54, does not detract from the length of the stick carrier, so that the entire length of this carrier can be 35 used for accommodating the lip sticks. On the other hand, with a given lip-stick length the whole pencil in this construction can be made shorter than with stick carriers according to Fig. 1.

40 I claim:—

1. A multiple pencil especially for make-up sticks, comprising in combination an outer case having a plurality of longitudinal slots, a plurality of stick carriers in said case corresponding 45 to the number of slots in said case, slide-knobs one connected with each of said carriers and each projecting through one of said slots and adapted to shift said carriers into and out of their position of use, a conical point rotatable on the front 50 end of said case and having at least one longitudinal groove, each of said carriers comprising a rotatable part having a helical slot, at least one lateral projection arranged on the front end of said rotatable part and adapted to engage 55 gage in said groove when its carrier is moved forward in said case to couple said rotary part with said conical point, a stick holder slidable in said carrier, a pin projecting radially from said holder through said helical slot, said pin adapted to slide in said helical slot during the 60 rotation of said conical point and to shift said holder forwards and backwards in said rotary part.

2. A multiple pencil as specified in claim 1, 65 in which the front end of the rotary part of each stick carrier has a multiple screw thread with steep pitch and the conical case point has longitudinal grooves corresponding to the screw threads.

70 3. A multiple pencil as specified in claim 1, in which each of the slots in the pencil case is widened laterally at its front end forming a shoulder adapted to engage the slide knob and 75 secure the corresponding stick carrier in its forward position, the rotatable part of the stick

carrier having at its rear end an abutment adapted to check the rearward movement of the stick holder, said rotatable conical point adapted to disengage said knob from said shoulder when said stick holder is in its rearmost position.

5 4. A multiple pencil as specified in claim 1, in which the slide knob of each stick carrier is sufficiently long to entirely cover its slot in the case when the stick carrier is in its position of rest, and each stick carrier is connected with 10 its slide knob by a blade spring adapted to cover the inner side of its slot when the stick carrier is in its position for use.

5 5. A multiple pencil as specified in claim 1, in which each stick carrier is connected with a 15 tubular sleeve arranged at its side, said sleeve accommodating a return spring.

6 6. In a multiple pencil as specified in claim 1, a blade spring projecting radially from the rear 20 end of each stick carrier and carrying the slide knob, a tubular sleeve mounted on said spring and extending parallel to said stick carrier, and a return spring accommodated in said tubular sleeve.

7 7. In a multiple pencil as specified in claim 1, 25 a blade spring projecting radially from the rear end of each stick carrier and carrying the slide knob, a tubular sleeve mounted on said spring and extending parallel to said stick carrier, and a return spring accommodated in said tubular 30 sleeve, a supporting plate fitted in the rear end of the pencil case and having a plurality of slots corresponding to the number of stick carriers, a rod extending into said stick carrier and carrying said spring, a thickened rear end on said rod 35 engaging one of said slots and supporting its stick carrier on said plate, and a holding plate on the rear side of said plate and having holes registering with said slots, the thickened rear end on each of said rods engaging in one of said 40 holes to maintain said stick carriers in position.

8. In a magazine pencil of the multi-lead type having a plurality of lead carriers, lead adjusting mechanism associated with each of said lead carriers for causing movement of the lead relatively to its lead carrier, a casing in which said lead carriers are mounted so that each is movable independently of the other carriers into a position in which it protrudes from the casing, movable means on the casing adapted to interlock 45 with the lead adjusting mechanism on each lead carrier, whereby movement of said movable means on the casing when it is interlocked with said lead-adjusting mechanism of a carrier, will cause the lead to move relatively to its carrier. 50

9. In a magazine pencil of the multi-pencil type having a plurality of lead carriers, lead adjusting mechanism associated with each of said lead carriers for causing movement of the lead relatively to said lead carrier, a casing in which 55 said lead carriers are mounted so that each is movable independently of the other carriers into position in which it protrudes from the casing, movable means on the casing adapted to interlock with the lead adjusting mechanism of each lead carrier, whereby movement of said movable means on the casing when it is interlocked with said lead adjusting mechanism of a carrier will cause the lead to move relatively to said carrier, 60

90 said interlocking of said movable means with the lead adjusting mechanism being effected by projections in said means adapted to fit into depressions in said mechanism.

10. A multiple pencil comprising in combination an outer case having a plurality of longi- 70

5 longitudinal slots, a plurality of writing point carriers in said case corresponding to the number of slots in said case, slide-knobs one connected with each of said carriers and each projecting through one of said slots, and adapted to shift said carriers into and out of their position of use, a conical point arranged on the front end of said case and having at least one longitudinal groove, each of said carriers comprising a rotatable part having a helical slot, at least one lateral projection arranged on the front end of said rotatable part

and adapted to engage in said groove when its carrier is moved forward in said case to couple said rotary part with said conical point, means for actuating the writing point slidably in said carrier, a pin projecting radially from said actuating means through said helical slot, said pin adapted to slide in said helical slot to thereby shift said actuating means forward and backwards in said rotary part. 5
